ALARM SETTING MECHANISM FOR ALARM CLOCKS

George Clay, Cricklewood, London, England, assignor to S. Smith & Sons (England) Limited, London, England, a British company

Filed June 20, 1958, Ser. No. 743,295

Claims priority, application Great Britain June 21, 1957
2 Claims. (Cl. 58—22)

This invention relates to alarm setting mechanisms for alarm clocks of the kind in which a rotatable setting element is arranged to impart rotational adjusting movement to a cam follower and to an indicating hand, which two parts are normally fixed and which follower co-operates with a cam rotated by the clock movement so that when a part of the cam is brought by its rotation opposite a part of the cam follower, the alarm mechanism is set into operation. It is usual, with such an arrangement, for a spindle to which the cam follower and hand are attached to pass through a boss on a wheel constituting a part of the transmission which drives the cam and thus there may be a tendency for the cam follower to creep from the position into which it has been set. An object of the present invention is to prevent such creep taking place.

According to this invention, an alarm setting mechanism of the kind referred to is characterised in that said cam follower is provided with a cylindrical boss, which is arranged opposite a cylindrical boss formed on a fixed part of the clock, which two cylindrical bosses are substantially the same in diameter and are closely encircled by the convolutions of a helical spring, the arrangement being such that any tendency for relative movement between the two bosses due to creep, causes the convolutions around the fixed boss to tightly grip it thus preventing the creep, while relative movement which takes place in setting the alarm has the tendency to unwrap the spring from the bosses whereby the setting movement is not substantially resisted.

In one construction according to the invention, an alarm setting knob is fixed to an axially movable spindle to which is fixed a pinion so that at one limit of axial movement, the pinion engages another pinion fixed to a second spindle carrying the indicating hand traversing a setting scale for the alarm and at the other limit of axial movement it engages a pinion in a transmission for setting the hands of the clock.

The pinion attached to the second spindle may have a boss whose end forms a cam face, formed with two similar notches spaced apart by 210° about the spindle, which notches have one radial face at right angles to a plane normal to the spindle axis and the other radial at an angle to said plane and which second spindle extends through a cam member, having teeth capable of dropping into the said notches.

The cam member may be formed at the end of a hollow boss fixed to a toothed wheel constituting a part of the transmission for driving the clock hands.

The aforesaid spindle may pass through this hollow boss and has the alarm pointer fixed to its extremity.

A shoulder may be formed between the cam member and the hollow boss which is engaged by an alarm release spring which tends to press the cam towards the cam follower.

The pinion to which the cam follower is fixed may be provided with a cylindrical boss which abuts a fixed boss on a part of the clock frame, the diameters of which two bosses are substantially the same, and they are encircled by a helical spring having convolutions which lightly and frictionally engage the surface of the two bosses. The direction of winding of this spring is such that when

2

the manipulating knob is moved in a direction to set the alarm hand the spring tends to unwrap; when, however, the hand has been set, the tendency for the cam follower to be rotated by the clock movement tightens the spring around the fixed boss, thereby holding the cam follower against any tendency to be moved from its set position by the rotation of the cam, which is of course in frictional engagement with it.

The following is a description of one form of alarm setting mechanism for alarm clocks according to the invention, reference being made to the accompanying drawings in which:

FIGURE 1 is a diagrammatic side elevation of the setting mechanism;

FIGURE 2 is a plan view of the cam follower shown in FIGURE 1; and

FIGURE 3 is an under plan view of the cam shown in FIGURE 1.

Mounted between the front and back plates 10 and 11 of the clock are various toothed wheels of the alarm operating mechanism (not shown) and various toothed wheels 12, 13 and 15 associated with the transmission for driving the clock hands (not shown). One of the wheels 12 has fixed thereto a wide pinion 14 which drives the toothed wheel 15. The toothed wheel 15 has a hollow hub portion 16 the lower end of which is formed with a cam member 17. A spindle 18 extends through and is rotatable in a hollow hub 16. The upper end of the spindle 18 extends through the front plate 10 and has attached to its extremity a pointer 19 which traverses an alarm setting scale (not shown). The lower extremity of the spindle 18 projects below the cam member 17 and through a pinion 20 to which it is fixed. The pinion is provided with cylindrical boss 21 which abuts another cylindrical boss 22 of the same diameter which is formed on back plate 11. The cylindrical surfaces of the two bosses are encircled by a helical spring 23. The upper face of the pinion 20 is formed with a cam follower 24. The pinion 20 may be engaged by an axially movable pinion 25 fixed to a spindle 26 provided with a manipulating knob 27. The spindle 26 is reciprocable in a bearing 28 attached to the back plate 11. At the upper limit of its movement the pinion 25 is brought out of engagement with the pinion 20 and into engagement with the toothed wheel 13 which is mounted on shaft 41 journaled in plates 10 and 11 and forms part of the transmission to the clock hands whereby the hands may be set.

The spindle 18 is fixed against axial movement and the toothed wheel 15 and its hub 16 and cam 24 may move axially upon it. The enlarged cam portion 17 provides a shoulder which is engaged by a spring blade 29, deflection of which in a downwards direction releases the alarm mechanism. Spring blade 29 may be curved as

at 40 to allow the passage of axially movable pinion 25 or may yield sufficiently to allow pinion 25 to mesh with toothed wheel 13. The spring blade also serves to maintain the cam 17 and cam follower 24 in contact. The direction of winding of the spring 23 is such that

when the manipulating member 27 is in a position in which the pinions 20 and 25 are in engagement and the manipulating member is rotated in a direction to set the pointer 19 and cam follower 24, the spring tends to unwrap. When, however, the pointer has been set any tendency there may be for the cam follower to be rotated out of its adjusted position by the spindle 18 tightens the spring around the two bosses 21 and 22 and since the latter is fixed the spindle 18 is prevented from rotation and from changing the setting of the cam follower.

As will be seen from FIGURE 2, the upper face of the cam follower 24 is provided with two notches 30 spaced apart by about 210°, each of which notches

is provided with a radial face 31 which is at right angles to a plane normal to the spindle axis and the other face 32 is inclined to a plane normal to the spindle axis. The cam member 17 is provided with inclined teeth 33 so disposed that during one part of rotation of the cam they can drop into said recesses 30 after passing over the ends of the faces 31, whereby axial movement is imparted to the cam member by the spring blade 29 thus releasing the alarm mechanism. The inclined portion of the teeth 33 eventually engage the inclined faces 32 whereby the alarm mechanism is reset.

While there have been described above what are presently believed to be the preferred forms of the invention, variations thereof will be obvious to those skilled in the art and all such changes and variations which fall within the spirit of the invention are intended to be covered by the generic terms in the appended claims, which are variably worded to that end.

I claim:

1. An alarm clock setting mechanism for alarm clocks comprising in combination with a clock mechanism having a frame and an alarm, a toothed wheel having a hollow hub portion the end of which is formed with a cam member, a spindle which extends through and is rotatable in said hollow hub, an alarm setting indicating pointer attached adjacent one end of said spindle, a pinion having a cam follower on one side and a first cylindrical boss on the other, a second cylindrical boss of the same diameter as and substantially aligned with said first boss and fixed to the frame, the other end of said spindle projecting through said hollow hub, through said pinion and into said fixed boss, a helical spring en-

circling the cylindrical surfaces of the two bosses, a rotatable setting element connected to impart rotational alarm setting adjustment to said cam follower, said helical spring encircling both said bosses in such a direction 5 that any tendency for relative movement between the two bosses in one direction due to creep causes the convolutions around the fixed boss to grip it tightly and prevent creep and any relative movement in the opposite direction which takes place in setting the alarm tends 10 to unwrap the spring from the bosses upon rotational alarm setting adjustment of said cam follower by said setting element, an alarm release spring, a shoulder formed between the cam member and said hollow hub, said shoulder being engaged by said alarm release spring 15 which tends to press the cam towards the cam follower.

2. The combination set forth in claim 1, said cam follower having two similar notches spaced apart by 210° about the spindle axis, each notch having one radial face 20 perpendicular to a plane normal to the spindle axis and another radial face at an angle to said plane, said cam having teeth constructed and arranged to mate with said notches and to actuate said alarm release spring and to cause the alarm to sound.
